His Attorney.

UNITED STATES PATENT OFFICE.

JOHN SCHREIBER, OF ST. LOUIS, MISSOURI.

SEWING MACHINE.

Original application filed May 21, 1921, Serial No. 471,314, now Patent No. 1,440,556, dated January 2, 1923. Divided and this application filed December 18, 1922. Serial No. 607,522.

This invention relates to sewing machines and has special reference to mechanism for feeding a locked thread through the loop of one thread that has been passed through the 5 loop of another thread to lock the looped threads together.

An object of the invention is to provide an improved locked thread feeding mechanism specially adapted for use in a machine of 10 the type disclosed in my prior application Serial No. 471,314, filed May 21, 1921, patented January 2, 1923, No. 1,440,556, in which said application and patent the present invention is disclosed and from which it 15 is divided. Although the present invention is specially adapted for use in the machine disclosed in my said prior application, I do not restrict myself to the use of the invention in that embodiment alone but desire to 20 claim the invention wherever used.

The broad object of the invention is to provide mechanism for use in machines in which the stitches are formed from a loop passing through a puncture in the layers of 25 material to be united, with the second loop inserted through the first-named loop on the side of the material opposite from its point of entry, and a lock thread inserted in the second loop to lock the two loops together 30 when the stitch is drawn within the material so as to protect it from wear.

Other objects will appear from the following description, reference being made to the drawings in which—

35 Fig. 1 is a side elevation of the frame supporting the lock thread feeding device and the operating mechanism therefor.

Fig. 2 is a vertical sectional view of the lock thread feeding mechanism.

40 Fig. 3 is a plan view of the lock thread feeding mechanism.

Fig. 4 is a front elevation of the same mechanism with the front cover plate removed.

45 Fig. 5 is an enlarged fragmentary plan view of a portion of the lock thread feeding device.

The lock thread 1 is operated by mechanism supported within a frame 2. A main 50 operating shaft 3 has an arcuate rack and gear segment 4 attached thereto for imparting intermittent movements to the lock thread feeding mechanism. The lock thread feeding mechanism is operated by a shaft 5

having a pinion 6 attached thereto with 55 which the rack or segment 4 meshes intermittently as the shaft 3 continuously rotates. The shaft 5 is composed of two axially aligned portions coupled by a sleeve 7 enclosing the adjacent ends of both portions of the shaft 60 5 and permitting the lock thread feeding mechanism and the frame 2 supporting it to be withdrawn easily without removing the other portion of the shaft 5. For this purpose that portion of the shaft 5 which extends into the frame 2 is slidable within a frame or sleeve 7.

The thread 1 passes through a channel 8 to a feeding device. The feeding device for the lock thread 1 comprises a ring 9 having 70 a circumferential flange 10 the periphery of which is provided with ribs arranged obliquely to the side edges to obtain better engagement with the thread 1 and to pass the thread along through a channel 11 (Fig. 2) 75 below the plane of the needle slot 12 formed through the work supporting plate 13. The feeding device thus formed is supported so that the flange 10 engages the thread 1 passing from the channel 8, and as the feeding 80 device is turned in its support the thread 1 is passed therefrom through the channel 11 to position to perform its function.

The ring 9 of the feeding device is within a support 14 having an opening somewhat 85 greater than the diameter of the ring 9. The flange 10 of the thread feeding device is between the support 14 and a plate 15, forming part of the housing of the feeding mechanism. A spring 16 (Figs. 2 and 4) in 90 the frame yieldingly supports the feeding device and presses the same to the position shown in Fig. 4, so as to engage and feed the thread 1 properly when the feeding device is rotated. From the channel 8 the 95 thread 1 passes upwardly between the periphery of the flange 10 and the adjacent wall of the support for the feeding device. As a result of this the spring 16 causes the 100 ribbed peripheral surface of the flange 10 to move the thread 1 around about one-fourth of the circumference of the feeding device and thence into the curved channel 11. A short rotary movement is imparted to the feeding device 9—10 by each intermittent rotary movement of the shaft 5 and the means for effecting this movement of the feeding device will now be described.

- The ring 9 is provided with an internal circumferential series of ratchet teeth 17. A pawl 18 is pivotally supported on a projection 19 from a vertically movable slide 20 and is pressed into engagement with the ratchet teeth 17 by a spring 21. During downward movement of the slide 20 the pawl 18 escapes over the teeth 17, but leaving the feeding device 9—10 stationary.
- Upward movement of the slide 20 imparts a short rotary movement to the feeding device 9—10 sufficient to pass the desired length of the thread 1 beyond the channel 11 and below the plane of the needle slot 12.
- The slide 20 supports rollers 22, one of which engages a cam 23 and the other of which engages a cam 24, both of which cams are attached to the forward detachable end portion of the jointed shaft 5. The cams 23 and 24 are constructed and arranged to impart vertical reciprocating movements to the slide 20, with the result that the thread feeding device 9—10 is intermittently rotated. After the thread 1 has been advanced to effective position and has been raised into a vertically widened portion 25 of the channel 11, the thread is cut to leave the end portion thereof in and as a part of a stitch.
- The knife 26 for cutting off the end portion of the thread 1 after each movement of the thread by the feeding device 9—10 is supported by a slide 27 arranged for vertical sliding movements similar to the slide 20. The upper portion of the slide 27 has a roller 28 operating against the cam 24 and the lower portion of the slide 27 has a roller 29 operating against a cam 30 on the shaft 5.
- As before stated upward movement of the slide 20 operates the thread feeding device 9—10 to pass the end of the thread 1 to effective position below the slot 12. After the thread has been advanced and extended to effective position the slide 27 is raised operating the knife 26 against the inner surface of the upper portion of the plate 15 and against the inner edge of the cover 31 of the housing. The vertically widened portion 25 of the channel 11 is within the cover plate 31. Upward movement of the knife 26 against the inner surfaces of the plates 15 and 31 is sufficient to cut the thread 1, after which the slide 27 is moved downwardly to carry the knife 26 below the lower wall of the channel 11, leaving the thread 1 free to be moved at the next operation of the feeding device 9—10. A spring 32 may be utilized to press the knife 26 against the plates 15 and 31.
- The stitch forming mechanism for utilizing the severed ends of the thread 1 constitutes the subject-matter of my prior application before mentioned from which application the present case is divided. There-

fore, the subject-matter of my said prior application is not shown or described in detail in this case.

From the foregoing it will be seen that my invention is sufficient and satisfactory for its intended purposes. It may be varied within equivalent limits without departure from the nature and principle of the invention. I do not restrict myself unessentially, but what I claim and desire to secure by Letters Patent is:—

1. In a machine of the character described, the combination of a thread guide, a shaft, a roll supported independently of said shaft, a flange on the roll for engaging the thread, a spring for pressing said roll to position to cause said flange to grip the thread, a pawl engaging said roll, and mechanism operated by said shaft for operating said pawl and thereby imparting intermittent and progressive rotary movements to said roll to rotate said roll in one direction only.

2. In a machine of the character described, the combination of a thread guide, a shaft, a roll, means independent of said shaft for supporting said roll, a spring for pressing the roll to position to grip the thread in said guide, a pawl engaging said roll, a movable slide supporting said pawl, and means operated by said shaft for operating said slide to cause said pawl to impart intermittent and progressive rotary movements to said roll to rotate said roll in one direction only.

3. In a machine of the character described, the combination of a thread guide, a shaft, a roll, means independent of said shaft for supporting said roll, a spring for pressing the roll to position to grip the thread in said guide, a pawl engaging said roll, a movable slide supporting said pawl, means operated by said shaft for operating said slide to cause said pawl to impart intermittent and progressive rotary movements to said roll to rotate said roll in one direction only, a knife, and means operated by said shaft for operating said knife to cut the thread.

4. In a machine of the character described, a thread guide, an annular rotary feed device for feeding the thread through said guide, ratchet teeth on said feed device, a support mounted for reciprocating movements, a pawl on said support engaging said ratchet teeth, and means for reciprocating said support to cause said pawl to impart intermittent rotary movements to said feed device.

5. In a machine of the character described, a thread guide, a rotary feed device for feeding thread through said guide, ratchet teeth on said feed device, a shaft, means for imparting intermittent rotary movements to said shaft, a support, means operated by said shaft for reciprocating said

support, and a pawl carried by said support engaging the ratchet teeth on said feed device for imparting intermittent rotary movements to said feed device.

5 6. In a machine of the character described, a thread guide, a ring, a circumferential flange in connection with said ring, ribs on the periphery of said flange for engaging the thread, ratchet teeth supported 40 by said ring, a reciprocating support, a pawl mounted on said support for engaging said ratchet teeth to impart rotary movements to 45 said ring and flange, and mechanism for reciprocating said support.

10 7. In a machine of the character described, a thread guide, a ring, a circumferential flange in connection with said ring, ribs on the periphery of said flange for engaging the thread, ratchet teeth supported 50 by said ring, a reciprocating support, a pawl mounted on said support for engaging said ratchet teeth to impart rotary movements to 55 said ring and flange, a shaft, cams on said shaft, and elements supported by said support 60 engaging said cams for reciprocating said support when said shaft is rotated.

15 8. In a machine of the character described, a thread guide, a ring, a circumferential flange in connection with said ring, ribs on 65 the periphery of said flange for engaging the thread, ratchet teeth supported by said ring, a reciprocating support, a pawl mounted on said support for engaging said ratchet teeth to impart rotary movements 70 to said ring and flange, a shaft, cams on said shaft, elements supported by said support engaging said cams for reciprocating said

support when said shaft is rotated, and means for imparting intermittent rotary movements to said shaft. 40

9. In a machine of the character described, a thread guide, a rotary feed device for feeding thread through said guide, ribs on the periphery of said feed device for engaging the thread, a spring for pressing the 45 feed device to position to engage the thread, an intermittently rotating shaft, and mechanism operated by said shaft for imparting intermittent rotary movements to said feed device. 50

10. In a machine of the character described, a thread guide, a rotary feed device for feeding thread through said guide, ribs on the periphery of said feed device for engaging the thread, a spring for pressing the 55 feed device to position to engage the thread, an intermittently rotating shaft, cams on said shaft, a reciprocating support operated by said cams, and means operated by said support for imparting intermittent rotary 60 movements to said feed device.

11. In a machine of the character described, the combination of a thread guide, a feed device for passing thread through said guide, a spring for pressing the feed device to position to engage the thread, an intermittently rotating shaft, mechanism operated by said shaft for imparting intermittent rotary movements to said feed device, a 65 knife for cutting the thread that has passed through said guide, and mechanism operated by said shaft for operating said knife to cut the thread. 70
